United States Patent Office.

DAVID L. McGREGOR, OF CHARLESTOWN, MASSACHUSETTS.

Letters Patent No. 72,812, dated December 17, 1867.

IMPROVED BACK-BAND FASTENER.

The Schedule referred to in these Letters Patent and making part of the same.

Be it known that I, DAVID L. McGREGOR, of Charlestown, in the county of Middlesex, and State of Massachusetts, have invented a new and useful Improvement in Back-Band Fasteners or Holders for Saddles, of which the following is a full, clear, and exact description, reference being had to the accompanying drawings, making a part of this specification, in which—

Figure 1 is a vertical longitudinal section of a saddle embodying my improvement.

Figure 2 is a perspective view of the same; and

Figure 3 is a modification of my invention.

Similar letters indicate like parts in the several figures.

The object of my invention is to obviate the difficulties incident to the mode of constructing the back-band fastenings for saddles, as generally used, such as the breaking away and stretching of the back-band and injury to the saddle, caused by the working or motion of the same; and the invention consists in forming the portion that connects the back-band to the saddle of metal straps, which may be attached directly to and be sustained by the saddle-tree, or be connected together at the top of the saddle-tree.

The fastening, as commonly used, consists of a strap of leather, which is carried over the saddle-tree and secured by the terret. The constant wear and motion of the back-band, when in use, causes the fastening to become stretched and frequently broken, thus requiring frequent repairs.

Referring to the drawings, *a* represents the saddle-tree, which may be made of wood or metal in the usual manner. *b* is the jockey, *c* is the flap, and *d d* are the terrets, all constructed and put together in the ordinary way. *e e* represent metallic straps of any suitable thickness and width. In fig. 1 they are represented as formed with a hook or curved portion at the upper end; which hook takes into an opening in the saddle-tree, as shown, where it will be firmly sustained. The terret-screw *d* passes through an opening made in the same, and serves to hold it firmly in position. The straps *e* project below the jockey, where a ring, *f*, is attached, which sustains the back-band. Instead of the hooks at the upper end of the strap *e*, the same may be screwed to the saddle-tree; or the said straps may extend to the top of the saddle, and be fastened to each other by a hook, formed upon one of the straps, engaging in a slot formed in the other, as shown in fig. 3, and in the latter may be several slots to admit of the straps being adjusted to different lengths. The straps or holders *e* may thus be very readily applied or detached, they cannot stretch, and are not liable to break, and by their application a finer finish can be given to the saddle than when the necessarily thick leather holder is used.

What I claim as new, and desire to secure by Letters Patent, is—

The metallic back-band fastener *e*, in combination with a saddle, substantially as described, and for the purpose set forth.

In testimony whereof, I have signed my name to this specification in the presence of two subscribing witnesses.

DAVID L. McGREGOR.
